MOLten METAL PUMP

Wayne A. S. Harmon, Los Angeles, Calif.

Application May 21, 1934, Serial No. 726,652

5 Claims. (Cl. 103—111)

This invention has to do with pumps for circulating molten metals or salts, for example molten lead, heated to high temperatures. Although the present pump may be regarded as having general utility for handling fluids of this character, it has been designed particularly for circulating molten metal in oil cracking systems in which the oil is subjected to cracking by heat carried in a continuously circulated 10 molten metal stream.

Under the existent high temperatures and fluid condition of the molten metal at such temperatures, a major difficulty is encountered in attempting to confine the metal against leakage from the pump and against flow into oil lubricated bearings and other parts which should be protected against the hot metal. Accordingly, one of my principal purposes is to provide a confinement or seal that will obviate 20 such difficulty by insuring that the molten metal will reach only those parts of the pump that have been purposely designed to accommodate the metal. In serving this purpose, I have provided a seal utilizing a high pressure fixed gas 25 in such manner as to confine the flow of molten metal within predetermined limits relative to the pump bearings and other parts.

Preferably, I provide two pump shaft bearings, one lubricated by the molten metal itself, and the other by oil. The seal, incorporated into the pump structure between the two bearings, acts to prevent access of the hot metal to the oil bearing, and also to return to the pumping chamber, molten metal flowing 35 past the metal lubricated bearing. The invention also includes various features in connection with the oil feeding and discharging system for the oil lubricated bearing, and also with reference to precautionary measures taken 40 to prevent fire within the pump due to flashing of the lubricating oil.

All these, however, as well as additional features and objects of the invention will be understood more fully and to best advantage from the following detailed description of a typical and preferred embodiment of the invention. Reference is had throughout the description to the accompanying drawings in which:

Fig. 1 is a general view, diagrammatic in parts, illustrating a heating system for oil cracking units in which the present pump is used for circulating molten metal;

Fig. 2 is a detailed sectional enlargement of the pump;

Figs. 3 and 4 are sections on line 3—3 and 4—4 of Fig. 2; and

Fig. 5 is a fragmentary section on line 5—5 of Fig. 4.

For the purpose of illustrating one adaptation

and use of the present type of pump, I first refer to Fig. 1 showing a heat circulating system for oil cracking plants and in which the heat carrying medium, molten metal, is circulated by my improved pump. I may state that oil conversion systems of this general character comprise the subject matter of my copending application on Oil cracking processes, Ser. No. 726,653, filed on even date herewith. 5

The oil cracking unit, generally indicated at 10, comprises a vertically extending shell 11 containing a plurality of tubes 12 into which the cracking stock is fed through inlet 13 and distributor head 14. In flowing down through the tubes, the charging stock is subjected to cracking and vaporization, the vapors flowing upwardly through the tubes counter-current to the oil streams into head 14 and discharging through outlet line 15. The unvaporized residuum drains into the base 11a of the shell and 20 is discharged through line 16. 10

Cracking tubes 12 are exteriorly heated by molten metal maintained in continuous flow through the shell 11 and within a circulating system passing through a retort 17 which constitutes the primary heat supply source. Retort 17 comprises a chamber 18 heated to high temperatures by combustion gases from burner 19, preheated air being supplied the burner via passage 19 and ports 20. The hot combustion 25 gases leaving chamber 18 flow through a passage 21 leading to a heating chamber 22 surrounding the cracking unit shell 11, and also through chambers 23, 24 and passage 25 joining with passage 21. 30

The heat transferring metal for the circulating system is initially charged into drum 26 contained within chamber 24 and exteriorly heated by the hot gases flowing to passage 25 and also to passage 27 leading from the bottom of the chamber. 35

The molten metal pump 28 takes suction from drum 26 through line 29, and discharges the metal stream through line 30 into the retort heating coil 31 within which the metal is heated to the temperature desired (for example 1000 to 1200° F., or above) in accordance with operating conditions within the oil cracking system. The heated metal stream flows from coils 31 through line 32 into the lower end of shell 11, thence upwardly in contact and heat transferring relation with tubes 12, and is finally discharged through outlet line 33 to be returned to drum 26. It will be noted that the lower portion of pump 28 as well as the entire remainder of the molten metal 40

circulating system are encased within the various chambers and passages conducting hot combustion gases from the retort, and that heat losses from the metal stream are thereby minimized and the necessary high temperatures effectively maintained. The circulation rate of gases flow- 45

ing through chamber 22 is controlled by damper 22a in outlet passages 22b, the damper in turn being controlled by suitable means in accordance with the molten metal temperature in line 33 5 leaving shell 11.

Referring now to Fig. 2, metal circulating pump 28 is shown to comprise a body 34 forming a pumping chamber 35 having an inlet 36 connecting with pump suction line 29 leading from drum 26. A pumping element, rotary impeller 37, is contained within chamber 35 and is carried on shaft 38 rotatively driven by motor 39, the shaft extending downwardly through a chamber 40 within casing 41 and through the pump body 34. 10 The motor 39 contains the usual suspension ball bearing structure commonly adopted in line shaft impeller pumps and which serves to support the rotative parts. Any difference in expansion between the pump shaft and the pump body is 15 taken care of by the provision of vertical clearance pockets 35a and 35b below and above the pump impeller. Leakage of the molten metal into space 35c above the impeller, drains back through opening 37a to the pump chamber at the suction 20 side of the impeller. It will be noted that the top and bottom clearance pockets 35a and 35c are the same diameter and that the areas on the top and bottom faces of the impeller between its outer periphery and the clearance pockets, 25 are the same. Consequently there is established a hydraulic balance on the impeller. It may be noted that by reason of the high density of the molten metal, on starting up the pump, the impeller and shaft may float upwardly until the 30 impeller starts pumping lead, which it does in a few revolutions, and that then the impeller and shaft return to their normal positions illustrated. 35

Shaft bearing 42, located above pumping chamber 35 and below a gas chamber 43, is lubricated by molten metal from chamber 35 via a manifold 44 leading from the pumping chamber outlet 45 and connecting through passages 46 with annular lubricant grooves 47 formed within the inner faces of the bearing. Manifold 44 also 40 communicates with gas chamber 43 at its lower end via passage 48. While, as will later appear, the molten metal is maintained at some predetermined level L in the float cylinder below the upper end of bearing 42, the metal will nevertheless be effectively distributed via manifold 44 of the connecting passages throughout the bearing, by reason of the velocity head acquired by the molten metal within outlet 45 and the point of discharge into manifold 44. 45

50 The rising of molten metal within the pump body above a predetermined level is prevented by a control system, generally indicated at 50, and involving the use of high pressure inert gas. The control system comprises a cylinder 51 connecting via pipe 52 with the lower end of gas chamber 43, and containing a float 53 carried on rod 54 extending through guide 55. The lower end of cylinder 51 connects with the pumping chamber 35 by way of pipe 56 leading into the pump inlet line 29. A suitable inert gas is fed to drum 26 under high pressure by pump 58 through lines 57 and 59 under control of valve 60, and to float cylinder 51 and gas chamber 43 by way of lines 61 and 62. 55

As particularly illustrated in Figs. 1 and 2, the pump body extends vertically through the top wall W of the retort heating chamber, and is positioned relative to the wall W so that the lower 75 portion of the pump containing the pumping

chamber, as well as the lower portion of cylinder 50 of the return line 56, are exposed directly to the hot gases, thereby insuring that the metal will be kept in fully heated and molten condition. The upper portion of the apparatus however, including the motor, and the hereinafter described upper oil lubricated bearing and the control apparatus for regulating the supply of inert gas to the gas chamber 43, are located above the top retort wall W outside the combustion gas zone, so that all these parts are kept at relatively low temperatures to prevent damage and deterioration by overheating. 5

During operation of the pump, the molten metal which lubricates bearing 42 rises through manifold 44 and the bearing itself, into the bottom of gas chamber 43. The molten metal reaching the gas chamber, immediately drains through pipe 52 into float cylinder 51. In order to preclude the possibility of the molten metal rising within the body above drain line 52, I introduce the fixed gas to cylinder 51 and under control of float 53, at sufficiently high pressure to keep the molten metal surface depressed to a level L below pipe 52. The admission of high pressure fixed gas to chamber 43 and cylinder 51 is regulated by valve 64 which in turn is operated through link 65 and arms 66 and 67, the latter being connected to float carrying rod 54. As the molten metal rises within cylinder 51 above level L, more gas is admitted past valve 64 to increase the pressure on the liquid surface and to depress it to the predetermined level to be maintained, and conversely as the liquid level falls. 10 20 25

The pump shaft extends through an oil lubricated bearing 68 located above the gas chamber 43, the bearing structure including a lantern gland 69 supplied with lubricant through line 70. Lubricant is also fed via line 71 into an annular oil groove 72 formed in the bearing surface near its lower end. In order to avoid overheating the bearing and lubricating oil, I surround the bearing 68 with a jacket 73 through which water is circulated from inlet 74 to an outlet 75. It is desirable to keep the bearing well flooded with oil, and for that reason there may be considerable oil drainage, from the bottom of the bearing. Accumulation of bearing oil drainage within the gas chamber is prevented by an oil slinger 76 keyed to the pump shaft and acting to throw the oil away from the shaft and against the body wall so that it may become trapped in annular trough 77. The oil drains from the trough through pipe 78 into float cylinder 79, from whence it is discharged through line 80 under control of valve 81 operatively connected through linkage 82 with float 83. The pump shaft is surrounded and cooled below the oil trough 77 by water circulated through jacket 84. 30 40 50 55

In order to insure that gas chamber 43 may be 60 completely purged of air that might otherwise support combustion of oil within the chamber, I provide communicating pipes 85 and 86 through which steam or any suitable inert gas may be passed to thoroughly scavenge the chamber before the pump is started into operation. A stationary, non-rotative cup 87 is placed about the shaft 38 and, as shown most clearly in Fig. 5, is attached to the upper end of the pump body by bolts 87a. The lower end of the cup structure 70 projects into the upper end of the body bore 34a and serves as a follower by means of which the packing in gland 69 may be taken up by tightening the nuts on bolts 87a, ample take-up clearance being provided at 87c. 65 75

Cup 87 is provided as a water receptacle for snuffing any flame that might result from flashing of oil leaking upwardly from the bearing into chamber 40, it being understood that the upper portion of shaft 38 may be quite hot by reason of the high temperatures existing within and below bearing 42. Water may be circulated through cup 87 continuously, or only when the occasion arises, by way of inlet 88 and outlet 89, both extending into chamber 40 through its bottom wall 90. The latter is secured to the annular body flange 81.

As a further precaution against fire within chamber 40, I provide pipe connections at 92 and 93 with shell 41 in order that steam may be passed through chamber 40 to snuff the flame if the bearing lubricant should happen to flash. The entire pump unit is supported by resting casing 41 on supports 94, and may be vertically aligned to a close degree of accuracy by adjusting screws 96 bearing against the supports.

Before starting the pump into operation and after the metal in drum 28 has become molten, gas is admitted under pressure to the drum above the liquid level via line 58, and the pressure is increased until the molten metal has become elevated through line 29 into the lower portion of the pump and float cylinder 51. A valve 98 is then opened to admit the inert gas into gas chamber 43 of the pump and also into float cylinder 51 to prevent the molten metal from rising above drain connection 52 between the pump and float cylinder. Additional gas pressure is now applied to drum 28 and the molten metal is elevated sufficiently to completely fill the circulating system to the top of the cracking unit shell 11. By opening vent valve 99 in line 100, gas or air may be expelled from the system as the latter fills with the molten metal, the valve controlled vent also serving as a means for determining when the lead has reached the high point in the system.

After the entire circulating system is filled with molten metal, valve 99 is closed and the circulating pump 28 is started into operation. It may be observed that in shutting down the lead circuit, it is only necessary to stop the pump, release the inert gas pressure and allow all the molten metal to drain back into drum 28.

50 I claim:

1. A molten metal pump comprising a body containing a pumping chamber and a gas chamber above the pumping chamber, a rotary pumping element in said pumping chamber, a shaft connected to the pumping element and extending within the gas chamber, a shaft bearing between said chambers and lubricated with molten metal forced longitudinally along the shaft from the pumping chamber, a cylinder 60 communicating with said gas chamber and with the pumping chamber and containing a body of molten metal fed from the gas chamber, a float in said cylinder, a high pressure gas supply line connecting with said cylinder and the gas chamber, and a gas flow control valve in said line operated by said float.

2. A molten metal pump comprising a body containing a pumping chamber and a gas chamber above the pumping chamber, a pumping element in said pumping chamber, a motor above the gas chamber, a shaft connecting the motor with the pumping element and extending within the gas chamber, a shaft bearing between said

chambers and lubricated with molten metal forced longitudinally along the shaft from the pumping chamber, an oil lubricated bearing above the gas chamber but below the motor, means for collecting oil draining into said gas chamber from the last mentioned bearing, and a float controlled oil outlet leading from said oil collecting means.

3. A molten metal pump comprising a body containing a pumping chamber and a gas chamber above the pumping chamber, a rotary pumping element in said pumping chamber, a shaft connected to the pumping element and extending within the gas chamber, a shaft bearing between said chambers and lubricated with molten metal forced longitudinally along the shaft from the pumping chamber, means for returning to the pumping chamber, molten metal flowing past said bearing into the gas chamber, the last mentioned means including means forming a chamber within which a body of the molten metal is maintained at a level below said gas chamber, means for communicating to both said gas chamber and to the surface of said body of molten metal, an inert gas under superatmospheric pressure, a shaft bearing above said gas chamber, means for circulating oil through the last mentioned bearing, and means in the gas chamber preventing the oil from draining down along the shaft into contact with the metal flowing upwardly through the first mentioned bearing.

4. A molten metal pump comprising a body containing a pumping chamber and a gas chamber above the pumping chamber, a rotary pumping element in said pumping chamber, a shaft connected to the pumping element and extending within the gas chamber, a shaft bearing between said chambers and lubricated with molten metal forced longitudinally along the shaft from the pumping chamber, a cylinder communicating with said gas chamber and with the pumping chamber and containing a body of molten metal fed from the gas chamber, a float in said cylinder, valve means controlled by said float for admitting gas under pressure to both the cylinder and to said gas chamber, a shaft bearing above said gas chamber, means for circulating oil through the last mentioned bearing, and means in the gas chamber preventing the oil from draining down along the shaft into contact with the metal flowing upwardly through the first mentioned bearing.

5. A molten metal pump comprising a body containing a pumping chamber and a gas chamber above the pumping chamber, a motor above the gas chamber, a pumping element in said pumping chamber, a shaft connecting the motor with the pumping element and extending within the gas chamber, a shaft bearing between said chambers and lubricated with molten metal forced longitudinally along the shaft from the pumping chamber, means for returning to the pumping chamber, molten metal flowing past said bearing into the gas chamber, a second shaft bearing above said gas chamber and below said motor, means for feeding oil to said second bearing, and means in said gas chamber preventing the oil from draining down along the shaft into contact with the metal flowing upwardly through the first mentioned bearing.
